UNITED STATES PATENT OFFICE.

PHILIP SMITH, OF FALL RIVER, MASSACHUSETTS.

GRATE.

Specification of Letters Patent No. 23,621, dated April 12, 1859.

To all whom it may concern:

Be it known that I, PHILIP SMITH, of Fall River, in the county of Bristol and State of Massachusetts, have invented certain new and useful Improvements in Grates for Burning Coal, &c.; and I do hereby declare that the same are described and represented in the following specifications and drawings.

To enable others skilled in the art to make 10 and use my improvements I will proceed to describe their construction and operation referring to the drawings in which the same letters indicate like parts in each of the figures.

15 Figure 1, is a front elevation of a grate with my improvements. Fig. 2, is a plan or top view. Fig. 3, is a section on the line z, z.

The nature of my invention consists in hanging the lower part of the front of the 20 grate on pivots so far below the top that when the bottom is swung out to form an opening for the removal of unburned coal, cinders, clinkers or stones it will carry the top of the plate in and press the upper plate 25 so hard against the burning coal that it will hold it up while the cinders and stones are being removed from under it. And in arranging the upper inner front plate to vibrate, so as to be pressed against the burning 30 coal by the vibration of the lower plate, and hold up said coal while the incombustible matter below it is removed. Also in making the front frame and front plate in separate pieces so that they may shrink and swell 35 with freedom without straining any of the parts which compose them.

In the accompanying drawings A, is the back of the grate box B, B, the ends and C, the front all of which are firmly fastened together making a strong rectangular grate 40 box, the form of which box may be varied if desirable.

D, D, are bottom grate bars with openings E, E, between them. This bottom grate is 45 arranged high enough to leave the open space F, below it for the ash pit.

The front C, is made in the form shown in Fig. 1, with an opening in it partially closed by the frame H, which is similar in 50 form to the front C, but narrower, and arranged to slide in perpendicularly, just behind the front C. The top bar of H is wider than the top bar of C, and comes below it, and it is perforated as shown at I, I, Fig. 1.

55 The opening in the frame H, is stopped by the plate G, so as to hold the coal, which

plate is provided with pivots J, shown in dotted lines some distance from the top, which pivots are arranged to turn in recesses, in the frame H, when the plate G, is vibrated. 60 This plate G, has the bars K, K, projecting down from its lower edge nearly or quite to the top of the bottom grate D. The plate G, is held in a perpendicular position by the plate or rack L, which extends nearly to the 65 top of the front and is hung on pivots M, M, which turn in recesses in the frame H.

The inside of the plate L, is shown in Fig. 4, and the outside in Fig. 5. It consists of three perpendicular bars N, N, connected by the bottom bar P, and top bar Q, the ends of the latter forming pivots to hold it in place, and allow it to vibrate. The inside of the bars N, N, are made wider than the outside, and arranged for the bars R, R, 70 to slip in between them; these bars R, R, being made narrowest on the outside and widest on the inside or just the reverse of the bars N, N, as shown in Figs. 6, and 7, the latter of which is an edge view of one of the 75 bars R, which bars have a piece across the top which prevents them from slipping down, as does also the wide part which rests on the bottom bar P. When these bars are put into the frame a plate is formed level 80 on both sides and the pivots are set off as shown in Fig. 3, so that the weight of the plate swings against the top of the plate G, and holds in perpendicular. The plates G, and L, being so constructed and arranged 85 that when the bottom of G, is swung out, its top acts on L, and pushes its lower edge in against the coal in the grate to hold it up while the operator pulls out the slag cinder or slate which has accumulated on the grate 90 D, in pieces too large to pass between the bars. The plate H, is fitted into the plate H', shown by dotted lines in Fig. 1, similar in form to the plate H, which plate H', is made to slide into the grooves S, S, shown 95 in Fig. 2.

The fire is kindled in this grate in the usual manner and after it has burned a while and that portion of the coal which does not burn to ashes has accumulated on 100 the grate bars with cinders, clinkers and stones, too large to pass through between the bars of the bottom grate but choke and obstruct the free burning of the fire, the attendant pulls out the bottom of the plate G, 105 with the poker, into the position shown by dotted lines in Fig. 3, which presses the 110

plate L, into the position shown by dotted lines in the same figure, so as to hold up the upper part of the burning coals in the grate while the attendant pulls the coal which 5 will not burn with the cinders, clinkers and stones off of the grate D, and they fall into the ash pit out of the way, when he pushes in the bottom of the plate G, and the plate L, releases the burning coals which it held 10 up and they fall onto the grate D, making room for a charge of fresh coal above them. In this way the fire may be continued a long time or until some part of the grate burns out.

15 By making the front of the grate in separate pieces as described and the plate L, the several parts may expand and contract with freedom without warping or breaking the other portions.

20 I believe I have described and represented my improvements in grates for burning

coal, so as to enable any person skilled in the art to make and use them.

I will now state what I desire to secure by Letters Patent to wit,

1. I claim hanging the front plate G on pivots arranged so far below the top that when the bottom is swung out, it will carry in its top and operate the inner upper plate L, as described for the purposes set forth. 25

2. I claim arranging the plate L, to vibrate substantially as described for the purposes set forth.

3. I claim the plates H, and H', constructed and arranged substantially as described. I also claim making the plate L, in separate pieces fitted together substantially in the manner described. 30 35

PHILIP SMITH.
